US0D1036763S

(12) **United States Design Patent** (10) Patent No.: **US D1,036,763 S**
(45) Date of Patent: ** Jul. 23, 2024

(54) **ELECTRONIC VAPORIZER**

(71) Applicant: **Shenzhen Itsuwa Technology Company Limited**, Shenzhen (CN)

(72) Inventor: **Ruyun Guo**, Shenzhen (CN)

(**) Term: **15 Years**

(21) Appl. No.: **29/791,293**

(22) Filed: **Jan. 6, 2022**

(51) LOC (14) Cl. **27-07**

(52) U.S. Cl.

USPC **D27/162**

(58) **Field of Classification Search**

(57) **CLAIM**

The ornamental design for an electronic vaporizer, as shown and described.

DESCRIPTION

FIG. 1 is a perspective top view.

FIG. 2 is a perspective bottom view.

FIG. 3 is a front view.

FIG. 4 is a back view.

FIG. 5 is a right side view.

FIG. 6 is a left side view.

FIG. 7 is a top view; and,

FIG. 8 is a bottom view.

The broken lines in the drawings depict portions of the electronic vaporizer that form no part of the claimed design.
